DRAFTSMAN'S TRIANGLE

Fred Tisch, West Shokan, N. Y.

Application January 11, 1952, Serial No. 266,035

1 Claim. (Cl. 33—104)

1

The present instrument relates to an instrument for drafting, and more particularly it relates to a draftsman's triangle.

It is an object of the present invention to provide a draftsman's triangle the inner edges of which have a series of irregular steps or notches which serve as predetermined measuring guides.

It is a further object of the present invention to provide a draftsman's triangle which has predetermined scales and graduations on both front and rear faces thereby adapting the triangle for both right and left hand calculations.

Moreover, it is an object of the present invention to provide a linear rule on one of the outer edges of the triangle, which rule permits computation on either side of a center line.

In addition, it is an object of the present invention to provide a triangle having a series of lines or graduations parallel to the hypotenuse for aid in cross-sectioning a drawing.

Still further, it is an object of the present invention to provide a triangle having edges which are unbevelled near the corners of the triangle so that the triangle will repose in a stable manner upon the drawing board.

Other objects and advantages of the present invention will become apparent as it is described in detail below with particular reference to the accompanying drawings, wherein

Fig. 1 is a view of the front face of the triangle embodying the present invention;

Fig. 2 is a view of the rear face of the triangle; and,

Fig. 3 is a cross-section taken on the line 3—3 of Fig. 1, and looking in the direction of the arrows.

With particular reference to Fig. 1, there is shown a transparent or translucent draftsman's triangle 11 which is known as the thirty, sixty degree type. The triangle 11 has edges 12, 13 and 14 which are partially bevelled at surfaces 15, 16 and 17, respectively. The bevelled surface 15 is located on the top face of the triangle 11, whereas the bevelled surfaces 16 and 17 are located on the rear face. These bevelled surfaces do not extend quite to the junctions where the edges intersect with each other so that the corner portions of the triangle 11 have flat top and under surfaces. This permits the triangle 11 to rest flatly upon the drawing board at all times, regardless of which face is in up position, and prevents any slight tilting or vibration due to pressure of the draftsman's hand as he holds the triangle in place.

Upon the bevelled surface 15 there is imprinted

2

or otherwise marked a linear rule 18. The center of this rule is marked by the numeral "0." Extending both upwardly and downwardly from the "0" mark, the rule 18 has linear graduations from the numerals 1 through 5. Since there are graduations reading both upwardly and downwardly from the "0" mark, it is possible for the draftsman to make rapid measurements on either side of a center line with a minimum movement of the triangle 11.

Although, as shown, there are no further linear rules or indicia upon the other bevelled surfaces 16 and 17, such measuring guides may be marked or imprinted thereupon, if desired.

Through the body of the triangle 11 there is an opening 30 defined by inner edges 19, 20 and 21. These inner edges 19, 20 and 21 of the triangle 11 each comprises a series of irregular notches or steps 31. On any edge, each step 31 is at a different and predetermined parallel distance from an adjacent step. Moreover, the length of each step differs from that of an adjacent step. Thus, the series of irregular steps on any one edge comprises a handy rule for the draftsman when a numeral guide is placed adjacent thereto as shown in Fig. 1. The first column of numerals of the guide indicates the length of each step and the second column of numerals indicates its distance from the next adjacent step. For example, if the draftsman wishes to measure a vertical line $\frac{1}{8}$ " long, he employs the step so marked as shown in Fig. 1. If he wishes to measure a horizontal distance of $\frac{3}{16}$ ", he employs the horizontal surface just below the $\frac{1}{8}$ " step.

The inner edges 20 and 21 also have appropriate guide rules, as shown in Fig. 2, indicating the length and distance of each step. However, these guide rules appear on the rear face of the triangle 11. Thus when the triangle is in the right hand position, as in Fig. 1, one set of guide indicia can be read. When the triangle is in the left hand position, as in Fig. 2, the remaining indicia of edges 20 and 21 can be easily read.

Parallel to hypotenuse edge 14 and on the rear face of the triangle 11 are a series of separate markings 22. These markings 22 are at various distances from the hypotenuse edge 14. Adjacent each marking is a numeral designating the distance of the marking from the edge. The purpose of these markings 22 is to permit the draftsman to cross-section a drawing or obtain accurate spacing of parallel lines. For example, if he wishes to measure parallel spacing of a dis-

tance of one-quarter of an inch, he aligns the particular graduation indicated at one-quarter of an inch over the reference line of the drawing and then draws a parallel line at the edge 14 of the triangle 11.

While the invention has been described in detail and shown with respect to the accompanying drawings, it is not to be limited to such details, since many changes and modifications may be made in the invention without departing from the spirit and scope thereof. Hence, it is desired to cover any and all forms and modifications of the invention which may come within the language and scope of the claim.

I claim:

A drafting triangle comprising a triangularly shaped flat body consisting of relatively thin material and presenting at its margins a series of straight edges collectively defining a triangle, said body being provided with an opening located wholly within the margins of said body and there defining a plurality of inner edges, each one of

which edges presents a series of different length steps disposed in a varying offset relation to each other, the steps included in any one of said series differing as to length and extent of offset from the steps included in each of the other of said series.
